UNITED STATES PATENT OFFICE.

ELPHEGE J. FOUNTAINE, OF WOONSOCKET, RHODE ISLAND.

POWER-TRANSMITTING MEANS.

No. 895,082.

Specification of Letters Patent.

Patented Aug. 4, 1908.

Application filed February 3, 1908. Serial No. 414,033.

To all whom it may concern:

Be it known that I, ELPHEGE J. FOUNTAINE, citizen of the United States, residing at Woonsocket, in the county of Providence and State of Rhode Island, have invented new and useful Improvements in Power-Transmitting Means, of which the following is a specification.

My invention has to do with power transmitting means through which one shaft may be rotated from another; and it contemplates generally the provision of means for the purpose stated possessed of characteristics calculated to assure transmission of motion without diminution of speed between the drive-shaft and the driven shaft.

With the foregoing in mind the nature of the invention and its novelty, utility and practical advantages will be fully understood from the following description and claim when the same are read in connection with the drawings, accompanying and forming part of this specification, in which:

Figure 1 is a view showing the drive-shaft and the driven shaft in section and also showing in elevation the power transmitter constituting the best practical embodiment of my invention of which I am cognizant. Fig. 2 is a plan view of the transmitter.

Similar letters designate corresponding parts in both views of the drawings, referring to which:

A is a drive-shaft, and B, a shaft to be driven from the said shaft A.

Grouped about the shaft A are two parallel sets of anti-friction rollers, the rollers C of one set being arranged opposite the centers of the spaces between the rollers D of the other set, and the two sets being made up, by preference, of four rollers each. It will also be seen by reference to Fig. 1 that the rollers in each set are arranged in a circular series and that the two sets of rollers are arranged parallel to each other.

Any means compatible with the purpose of my invention may be employed to support the rollers C and D about the shaft A and to effect connection between the disks and said shaft, without involving departure from the spirit of my invention. I prefer, however, to employ for the purpose disks C' and D' fixed on the shaft; the disk C' being provided with lateral inwardly directed journals a on which the rollers C are mounted and retained, and the disk D' being provided with

lateral inwardly directed journals b on which the rollers D are mounted and held. I prefer, of course, to have the rollers C and D revolve about their respective journals, and when deemed expedient anti-friction means (not shown) may be interposed between the rollers and journals.

Fixed on the driven shaft B is a circular plate E which is of a diameter to reach between the sets C and D of rollers grouped about and connected with the shaft A, and at opposite sides of the said plate E and fixed with respect thereto are ribs or lateral projections C² and D²; the rib or lateral projection C² being arranged to coöperate with the rollers C, and the rib or projection D² to coöperate with the rollers D. As will be observed by reference to Fig. 1, the ribs or projections C² D² respectively comprise four (more or less), equidistant protuberances c which are rounded as shown, and inwardly curved portions d arranged intermediate the said protuberances; and it will also be understood by comparing the full and dotted lines in said figure that the protuberances c of the rib or projection C² are arranged opposite the centers of the spaces between the protuberances c of the rib or projection D² and vice versa, this in order to enable one of the rollers C by coöperating with a protuberance c of the rib or projection C² to turn the shaft B through a part of a revolution, followed by a turning of the said shaft through a part of a revolution by the coöperation of one of the rollers D and a protuberance c of the rib or projection D².

In the practical use of my improvements it will be manifest that on rotation of the shaft A in one direction the shaft B will be rotated in the opposite direction, and this without the diminution of speed between the shafts. It will also be manifest that the transmission of motion is attended by but a minimum amount of friction. This latter is due in large measure to the rounded protuberances c and the inwardly curved portions d opposed to the rollers C and D.

It will be gathered from the foregoing that in addition to effecting connection between the ribs or projections C² and D² and the shaft A, the circular plate E serves because of its arrangement, relative to the rollers C and D, to retain each of the ribs C² and D² in alinement with its respective complement of rollers.

Having described my invention, what I claim and desire to secure by Letters-Patent, is:

In power transmitting means, the combination of two parallel shafts; parallel disks fixed on one of said shafts and disposed at right angles thereto, circular sets of anti-friction rollers carried by said disks; the rollers of one set being arranged opposite the spaces between the rollers of the other set, and the two sets resting between the disks and adjacent to each other, and a circular plate fixed on and disposed at right angles to the other shaft and extending between and arranged parallel to the sets of rollers on the parallel disks and having at its opposite sides

and fixed with respect thereto continuous, curvilinear, lateral ribs or projections which respectively comprise equi-distant protuberances and inwardly deflected portions intermediate the protuberances; the protuberances at one side of the plate being disposed opposite the middles of the spaces at the opposite side of the plate. 20

In testimony whereof I have hereunto set 25 my hand in presence of two subscribing witnesses.

ELPHEGE J. FOUNTAINE.
